RICHARD T. NEWTON, OF NEW YORK, N. Y.

VIBRATORY MACHINE

Application filed November 22, 1929. Serial No. 408,999.

This invention relates, generally, to vibratory machines; and the invention has reference, more particularly, to machines for performing vibratory body massage for remedial or hygienic purposes.

Vibratory machines as heretofore generally constructed have been somewhat unsatisfactory in use for the reason that whenever it is desired to vary the length of stroke or the amplitude of vibration of such a machine during a treatment it is necessary to stop the machine before the adjustment can be made, resulting in inconvenience to the user and the prolonging of the period necessary for treatment. Also, such machines commonly in use are rather complicated in structure and are therefore usually expensive.

The principal object of the present invention is to provide a novel vibratory machine which is adapted to have its amplitude of vibration readily and easily varied while the machine is running, the range of such variation extending from zero to any value desired up to the maximum for which the particular machine is designed.

The invention has for another object to provide a vibratory machine of the above character which is of simple and cheap construction as well as reliable in operation.

Other objects of this invention, not at this time more particularly enumerated, will be clearly understood from the following detailed description of the same.

The invention is clearly illustrated in the accompanying drawings, in which:

Fig. 1 is a plan view of the novel vibratory machine of this invention;

Fig. 2 is a view in side elevation looking at the left side of the structure shown in Fig. 1 with parts of the supporting pedestal broken away;

Fig. 3 is a sectional view taken along line 3-3 of Fig. 1 with parts omitted; and

Fig. 4 is a part sectional view taken along line 4-4 of Fig. 1.

Similar characters of reference are employed in all of the hereinabove described views to indicate corresponding parts.

Referring now to the said drawings, the novel vibratory machine of this invention

comprises a pedestal or supporting post 1 upon which is mounted a stationary base 2 having a socket 3 for receiving the upper portion of pedestal 1. Base 2 is secured in fixed position upon the pedestal 1 as by a key 4. A vertical headed stud 5 is threaded into a recess provided in the upper surface of base 2 over the pedestal 1. Stud 5 extends through a bushing or sleeve 6 and through an aperture provided in a horizontal forwardly extending bracket 7. The head of stud 5 presses the bracket 7 against the bushing 6 and this bushing against the upper surface of base 2, thereby rigidly holding these members together in fixed relative positions.

A swivel motor base 8 is positioned on top of base 2 and has a vertical apertured bearing portion 10 which is swivelly mounted on the bushing 6. Motor base 8 is formed with a forwardly projecting tapered portion 11 terminating in a handle 12 which extends beyond the forward marginal edge of base 2. This forward marginal edge of base 2 is curved along a circular arc having the length of a quadrant of a circle and the vertical axis of stud 5 as a center and is provided with a plurality of vertically extending serrations 13. A catch 14 is pivotally mounted on a pin 15 carried at the underside of handle 12 and has a tongue 16 adapted to engage any one of the serrations 13. A compression spring 17 is positioned between the underside of handle 12 and catch 14 and presses this catch so that its tongue is urged into a serration 13, thereby locking handle 12 and motor base 8 against relative turning movement about bushing 6 and with respect to base 2.

The rear portion of motor base 8 is transversely enlarged to receive and support an electric motor 18 which is secured to base 8 as by screws 19. The armature shaft 21 of motor 18 extends in the direction of the handle 12 and the forward end portion of this shaft has the hub of crank 22 secured thereto as by set screws 23. The hub of crank 22 is provided with an annular groove or recess 24 into which projects the forked upper end of a thrust plate 25. The lower end portion of thrust plate 25 is secured as by screws 26 to the bearing portion 10 of the motor base. Thrust

plate 25 absorbs the end thrust of armature shaft 21 and prevents end play of this shaft.

The crank pin 27 is formed eccentrically on crank 22 and projects through a central bearing aperture provided in a yoke 28 constituting an element of a universal joint or coupling. A screw 32 is threaded into the end of crank pin 27 and retains a washer against one side of yoke 28, thereby retaining this yoke upon the crank pin. The transverse oppositely extending trunnions formed on yoke 28 have bearings in a frame 30 which in turn is provided with vertical oppositely extending trunnions having bearings in the enlarged 10 forked inner end of a connecting rod 31. The central vertical axis of the trunnions of frame 30 is substantially aligned at all times with the axis of stud 5 so that the swivel motor base 8 and motor 18 may be freely turned 15 about the bushing 6 by means of handle 12, which turning movement merely causes the trunnions of frame 30 to turn within their bearings in the connecting rod 31 without appreciably moving the connecting rod. Inasmuch as the curved forward marginal edge of 20 the base 2 has the length of a quadrant of a circle, the handle 12 may be turned through an angle of 90°, or from its position illustrated in Fig. 1, wherein the connecting rod 31 is at right angles to crank 22 and shaft 21, to a position wherein this connecting rod is aligned with the crank 22.

The connecting rod 31 is illustrated as formed in halves which are secured together 25 by screws 33. The outer end of connecting rod 31 is also forked and is pivotally connected to the trunnions of a vertical yoke 34 of a second universal joint. Yoke 34 is provided with a transverse bearing aperture 30 through which a joint pin 35 extends. Joint pin 35 has its ends fixed in recesses provided in a transverse rocker arm 36. The universal joint comprising yoke 34 and pin 35 universally connects the outer end of 40 the connecting rod 31 to the rocker arm 36. This rocker arm 36 is formed midway of its length with a depending portion 37 having a central vertical bearing aperture extending therethrough. Depending portion 50 37 rests upon the bracket 7 and is rotatably mounted on a bolt 38 which extends through the aperture in this portion and is threaded through an aperture in bracket 7. Yokes 39 are attached to the ends of the rocker arm 36 55 and the ends of a strap or belt 41 are detachably connected to these yokes as by clips 42.

In operation, with the motor 18 running, the crank 22 acting through its crank pin 27 and the universal coupling 28-30 imparts rotary motion to the inner end of the connecting rod 31 which motion is transmitted by the outer end of this rod through coupling 34-35 as a reciprocating motion to the rocker arm 36, causing this rocker arm to oscillate about 60 its pivotal bolt 38. With the connecting rod 35

31 at right angles to the crank 22 as illustrated in Fig. 1, the plane of motion of a point on crank pin 27 coincides with the longitudinal axis of the connecting rod, thereby causing the connecting rod to impart a maximum oscillatory or vibratory movement to the rocker arm, whereas when the connecting rod is aligned with the axis of crank 22 and the motor shaft, the plane of motion of a point on crank pin 27 will be at right angles to the longitudinal axis of the connecting rod, resulting in a mere oscillatory movement of the inner end of the connecting rod without moving the rocker arm. At any point intermediate these two extreme positions, the crank 22 will impart vibratory motion to the rocker arm of an amplitude depending upon the angle which the connecting rod makes with the crank axis. As this angle is reduced from 90° the amplitude of vibration of the 85 rocker arm decreases proportionally.

This method of varying the amplitude of vibration of the rocker arm renders it a simple matter to change from one amplitude to another at any time whether the motor 18 is 90 running or idle. It is merely necessary to grasp handle 12 and upon pressing upwardly on catch 14, thereby releasing tongue 16 from a serration 13, the handle together with motor 18 may be moved to obtain any amplitude of vibration desired. This is highly desirable for it is important to vary the massage action from time to time during a treatment. Catch 14 retains the handle 12 in any position in which it is set.

The thrust plate 25 absorbs the end thrust of shaft 21 and causes all of the motion of this shaft to be properly imparted to the connecting rod 31 as desired. Owing to the positioning of coupling 28-30 above the stud 5, the motor 18 and its base 8 may be readily turned about this stud without appreciable friction, the trunnions of member 30 merely turning in the forked inner end of connecting rod 31.

It will be noted that the novel vibratory machine of this invention is of extremely simple and strong construction. It is apparent that the principles of this invention may be employed in other uses in addition to the one referred to in this specification.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. A vibratory machine of the character described comprising, a stationary base, a motor having a base turnably mounted on said stationary base, said motor having a ro- 130

tatable motor shaft, a rocker arm pivotally mounted on said stationary base, and means connecting said rocker arm to said motor shaft and acting to translate the rotary movement of said motor shaft to a vibratory movement of said rocker arm, said connecting means being so constructed and arranged as to cause the amplitude of vibration of said rocker arm to vary as said motor base is turned on said stationary base.

2. A vibratory machine of the character described comprising, a stationary base, a swivel motor base pivotally mounted on said stationary base, a motor carried by said motor base, said motor having a rotatable shaft, a rocker arm pivotally mounted on said stationary base, and means connecting said rocker arm to said motor shaft and acting to translate the rotary motion of said motor shaft to a vibratory motion of said rocker arm, said connecting means being so constructed and arranged that when said motor base is turned through an angle about its pivoted connection with said stationary base, the amplitude of vibration of said rocker arm is varied proportionally to the magnitude of said angle.

3. A vibratory machine of the character described comprising, a stationary base, a motor having a base pivotally mounted on said stationary base, said motor having a rotatable motor shaft, a crank secured to said motor shaft, a rocker arm pivotally mounted on said stationary base, a connecting rod having its inner end universally connected to said crank and its outer end universally connected to said rocker arm for translating the rotary motion of said crank to a vibratory motion of said rocker arm, said motor base being turnable about its pivotal connection with said stationary base during the operation of said motor to effect variation in the amplitude of vibration of said rocker arm.

4. A vibratory machine for body massage comprising, a stationary base, a motor having a base pivotally mounted on said stationary base, a handle formed on said motor base for turning said motor about its pivotal connection with said stationary base, means for retaining said handle in any desired position, said motor having an armature driven motor shaft, a crank secured to said shaft, a rocker arm pivotally mounted on said stationary base, a connecting rod having its inner end universally connected to said crank and its outer end universally connected to said rocker arm for translating the rotary motion of said crank to a vibratory motion of said rocker arm, and a belt attached to the ends of said rocker arm for effecting body massage, the amplitude of vibration of said rocker arm being varied at will while said motor is running from a maximum when said handle is at one extreme position to zero when said handle is at its other extreme position.

5. A vibratory machine for body massage comprising, a stationary base, a supporting stud extending upwardly from said base, a motor having a base pivotally mounted on said stud, a handle formed on said motor base for turning said motor about said stud, means for retaining said handle in any desired position, said motor having an armature driven motor shaft, a crank secured to said shaft, a rocker arm pivotally mounted on said stationary base, a connecting rod having its inner end universally connected to said crank and its outer end universally connected to said rocker arm for translating the rotary motion of said crank to a vibratory motion of said rocker arm, the universal connection at the inner end of said connecting rod being positioned over said supporting stud, and a belt attached to the ends of said rocker arm for effecting body massage, the amplitude of vibration of said rocker arm being varied at will while said motor is running from a maximum when said handle is at one extreme position to zero when said handle is at its other extreme position.

In testimony, that I claim the invention set forth above I have hereunto set my hand this 20th day of November, 1929.
